CLAIM

The ornamental design for a pressure washer spray gun,
as shown and described.

DESCRIPTION

FIG. 1 is a bottom and right side perspective view of a pressure washer spray gun, showing our new design;
FIG. 2 is a right side elevational view thereof;
FIG. 3 is a top plan view thereof;
FIG. 4 is a bottom plan view thereof;
FIG. 5 is a front elevational view thereof; and,
FIG. 6 is a rear elevational view thereof.
The barrel is shown broken away in FIG. 1 for ease of illustration. The hoses are shown broken away in FIGS. 1, 2 and 4-6 to indicate indeterminate length.

FIG. 3.FIG. 4.FIG. 5.FIG. 6.
